UNITED STATES PATENT OFFICE.

JOSEPH T. NORMAN, OF NANTICOKE, PENNSYLVANIA.

COAL BREAKER.

Application filed June 3, 1925. Serial No. 34,707.

The invention generally relates to coal breakers and primarily has for its object to provide a simple and effective machine of the class stated in which means is provided for imparting a real breaking action to the coal whereby to obtain the maximum of the potential commercial value thereof without the great waste now commonly occasioned by crushing and pulverization.

I am aware that many and various types of machines have been designed for a purpose kindred to that of my invention but such machines are undesirable or impractical because of the great waste occasioned by unnecessary pulverization of the coal. Among these types, those commonly used effect a breaking of the coal by impact in the nature of sharp blows, by a crushing action either by close engaging parts or by varied speed traveling agencies, or by opposed toothed rollers. Of these types the latter is probably the most practical and most commonly employed but is itself open to serious objection for several reasons, viz, the excessive pulverization of the coal by improper coordination of the rollers, the loss by pulverization due to the necessity of the coal falling a relatively great distance to and from the rollers, the great amount of work and expense in time and labor necessary in the adjustment of the relation of the rollers (it being necessary to completely remove and change driving gears and sometimes the rollers themselves), and because of the fact that it is possible for flat pieces of coal to fall freely flatwise through the rollers and the attendant necessity of regrading and re-treating such pieces.

Therefore, my present invention, addressed to the efficient elimination of the ills above enumerated, has for a more detailed object to provide means for breaking the coal by a pressure action so imparted as to assure cleavage thereof into the largest pieces possible and with a substantial elimination of all waste.

With the above and other objects in view that will hereinafter appear the invention further resides in the novel details of construction, combination and arrangement of parts, all of which will be first fully described, then be particularly pointed out in the appended claims, reference being had to the accompanying drawings, in which:

Figure 1 is a diagrammatic longitudinal section illustrating the invention.

Figure 2 is a somewhat diagrammatic cross section of the invention and serves to illustrate the means for transmitting power to and adjusting the position of the moving parts thereof.

Figure 3 is a plan view of the grader and feeder hopper.

Figure 4 is a cross section taken on the line 4—4 on Figure 3.

Figure 5 is a diagrammatic plan view showing the cooperative arrangement of the pins of the breaker elements.

Figure 6 is a detail end view of a section of the endless conveyor which forms the breaker table.

In the drawings, 1 indicates a receiving hopper having the usual flared receiving throat-way and a depending abutment skirt 2 and forwardly extended neck portion 3.

A suitable supporting table or guideway 4 may be provided to serve as a supporting medium for the reciprocable grading and screening table 5 provided with side wings 6 and a receiving floor composed of a plurality of longitudinally positioned spaced rollers 7 mounted in suitable bearings at the ends of the table and to which rotation (in like direction to all rollers) is transmitted through the connections 8 from the pulley connections 9 to which said motion is initially imparted. A suitable pitman 10 is connected to the table, as at 11, and an eccentric 12 with which the pitman has a strap connection 13, serve to impart reciprocatory motion to the said table 5.

The neck portion 3 with which the hopper is provided may extend substantially to the fore end of the reciprocable table 5 and it will be readily understood that as the coal to be crushed is fed into the hopper it will be deposited upon the said table and as the forward stroke of reciprocation takes place the said coal will be fed along that table and off its fore or discharge end. Each time the table moves forwardly an additional amount of coal will be allowed to fall down upon the same adjacent the abutment skirt 2 and upon the succeeding rearward movement of the said table that skirt will act to force the coal forwardly, thus effecting a step by step positive feed of the coal off the fore end of the said table. By reason of the spaced relation of the rollers 7 of the table and the fact that they rotate in like direction the function of that table will be to tend to turn edgewise such flat

pieces of coal as are small enough to fall through the spaces between the rollers, thus serving both to grade the coal to the desired size and to screen the same of slate 5 and the like. Also, by rotating all of the rollers in like direction it is impossible for any of the coal lumps to lodge between the same and clog the mechanism.

The discharge end of the table 5 is positioned so as to discharge, at a low point, upon the receiving end of the endless conveyer table 14 which includes side chains 15 adapted to pass over sprockets 16 on the cross shafts 17 and is composed of closely 15 positioned slats. The slats 18 are each provided at one edge with a convexly curved portion 19 terminating in an outwardly positioned abutment shoulder 20 and at the other edge with a concave portion 21 terminating 20 in an abutment edge 22. The concave portion of one slat is adapted to receive the convex portion of the adjacent slat and the abutment shoulder 20 to cooperate with the abutment edge 22 and provide a substantially 25 continuous flat conveyer table which will not readily sag under its own weight and that of the coal.

The upper table forming or travel portion of the conveyer 14 passes over a supporting table 23 adapted to provide a rest for that portion of the conveyer and to absorb all pressure and shock applied thereto.

Each conveyer slat 18 is provided with a plurality of centrally disposed equi-distantly spaced pins 24 extending longitudinally thereacross, the spaces between the pins on each slat and those of adjacent slats being such that considered longitudinally and crosswise all pins are equi-distantly 35 spaced, and a plurality of said pins are adapted to provide a rest for a single lump of coal. A breaker roller 25, pin studded as at 26, is positioned centrally above and in opposed relation to the upper travel portion 40 of the conveyer table 14. The breaker roller is adjustable as to its opposed relation with the said conveyer and is adapted to be rotated at a relatively slow speed, say for example from thirty to thirty-five revolutions per minute in a manner soon to be described, and the pins 26 with which the roller is provided are so positioned thereon that each thereof is adapted to cooperate or be centrally disposed with relation to a plurality of the pins 24 of the said conveyer. By reference to Figure 5 the positioning of the pins 24 of the conveyer table 14 and the relative positioning of those 26 of the roller 25 and the cooperating function thereof will be readily apparent. It will also be observed by reference to Figure 1 of the drawings that the pins 26 project from the said roller 25 somewhat tangentially in the direction of rotation of that roller so that the said pins will be caused

to engage the coal lump in a manner whereby the force exerted thereby will be directed to the axis of each said pin.

A take-off chute 27 is provided and positioned with the receiving end thereof closely adjacent the discharge end of the conveyer table 14 so as to receive the broken coal discharged therefrom.

It will be understood, of course, that one of the shafts 17 of the conveyer 14 is an idler while the other has rotative motion imparted thereto. The means for imparting movement to the endless conveyer table 14 and the roller 25 will now be described.

The roller 25 is provided with trunnion extensions 28, one of which has securely mounted thereupon a large gear 29 to which power is transmitted by the smaller driver pinion 30 which meshes therewith and is mounted upon the driver shaft 31 upon one end of which is mounted the loose pulleys 32-33 to which power is applied by suitable belt transmission, the belt being arranged to travel horizontally so that vertical adjustment of the shaft 31 will not effect the said power transmission.

The shaft and trunnions 31 and 28 have bearings in the connector bearing member 34 so that when the roller is adjusted the relation of the driver shaft therewith will be retained, or in other words the roller 25 and the driver shaft will be moved in unison when adjustment of said roller is effected. The bearing members 34 are vertically slidable in brackets 35 and each member 34 is provided with a lateral extension 36 between which and the arms 37 extending from the brackets 35 are interposed springs 38 which serve to normally hold the roller 25 down to its adjusted position while providing a yielding means so that should a lump of stone or iron be passed between the said roller and the conveyer table the roller would be permitted to yield upwardly and thus prevent breakage of the pins thereof.

An adjuster shaft 39 is provided and mounted in suitable bearings 40. The shaft 39 is provided with a large driven gear 41 to which rotative motion is imparted through the medium of the small pinion 42 meshing therewith and mounted on the crank shaft 43 which is in turn mounted in suitable bearings and provided with a crank 44 by which the rotative motion may be imparted for effecting the adjustment of the roller 25. The shaft 39 has secured to each end thereof a bevel gear 45 adapted to mesh with a similar bevel gear 46 rotatably confined in suitable bearings and thread bored to permit passage of the adjuster screws 47 provided at their upper ends with suitable bearing buttons 48 which engage sockets 49 in the underside of the extensions 36 of the bearing members 34.

From the foregoing it will be understood that as the crank 44 is turned rotative motion will be imparted to the shaft 39 and the confined bevel gear 45 rotated. Movement of the confined gears 45 will effect vertical movement of the screws 47 causing the roller 25 to move upwardly away from relation with the conveyer table 14 and against the tension of the springs 38, thus permitting adjustment of the opposed relation of the said roller and table according to the size of the coal to be crushed.

By reason of correlative positioning the pins of the roller 25 and the conveyer table 14 as illustrated in Figure 5 of the drawing and by driving the said parts at the same peripheral speed, means is provided for breaking the coal into the largest commercial sizes possible without grinding or crushing action such as will cause undesired pulverization.

For driving the conveyer table 14 at the same surface speed as that of the roller 25 one trunnion 28 and one shaft 17 may be connected by like sized sprockets and chain transmission devices 59. Obviously gear train transmission would be the equivalent of the means just above disclosed.

Figure 1 of the drawings illustrates one unit of adaptation of the invention. It should be understood that a plurality of such units may be positioned one above the other so that the small size coal lumps will fall through the greater table onto the hopper of the unit below so as to be treated in a similar manner as herein described and so on down through several such units until practical commercial sizing of the coal has been completed.

While I have disclosed herein means for feeding the coal to the breaker devices and for separating and grading the same while so feeding it, I make no claim in this application to that means as it forms the subject matter of a copending application which is a division of the present one.

From the foregoing description, taken in connection with the accompanying drawings, it is thought that the novel details of construction, the manner of operation and the advantages of my invention will be readily apparent to those skilled in the art to which it relates.

What I claim is:

1. In a device of the class described, a moving table having projections so spaced that a plurality thereof will provide supports for a lump of coal, a second movable member opposed to the movable table and having breaker pins projecting therefrom, and means independent of the coal being broken for moving said table and said member cooperatively to cause their adjacent surfaces to move substantially at like speeds and in like direction for causing the pins of

said member to engage the lumps of coal supported by each plurality of projections of said table intermediately of said projections.

2. In a device of the class described, a moving table having projections so spaced that a plurality thereof will provide supports for a lump of coal, a second movable member opposed to the movable table and having breaker pins projecting therefrom, and means independent of the coal being broken for moving said table and said member cooperatively to cause their adjacent surfaces to move substantially at like speeds and in like direction for causing the pins of said member to engage the lumps of coal supported by each plurality of projections of said table intermediately of said projections, and means for adjusting the relation of said table and member toward and from each other.

3. In a device of the class described, an endless conveyer table composed of closely related slats having coal lump supporting projections, a rotatable roller positioned adjustably above and in opposed relation to the conveyer table and having breaker pins projecting therefrom, a supporting table beneath the conveyer and the roller thereabove and over which the former rides to be supported against the coal breaking action, and means independent of the coal being broken for imparting motion to the roller and the conveyer table at like surface speed and in a manner for presenting each pin thereof cooperatively intermediately of a cooperating plurality of conveyer table projections.

4. In a device of the class described, a moving table having projections so spaced that a plurality thereof will provide supports for a lump of coal, a rotatable roller opposed to the movable table and having breaker pins projecting therefrom, in forwardly inclined relation to a radial position, whereby to cause said pins to engage the coal substantially axially and intermediately of and in substantially parallel relation to a plurality of coal lump supporting projections at a point in advance of the axis of said rotatable roller and means independent of the coal being broken for moving said table and for rotating said roller cooperatively for causing the pins of said roller to engage the lumps of coal supported by each plurality of projections of said table substantially axially and intermediately of said table projections.

5. In a device of the class described, a movable table having projections so spaced that a plurality thereof will provide supports for a lump of coal, a rotatable roller opposed to the movable table and having breaker pins projecting therefrom, means for causing the roller and table to move co-

operatively whereby their adjacent surfaces will move substantially at like speeds and in like direction for causing the pins of said roller to engage the lumps of coal supported by each plurality of projections of said table intermediately of said projections, a driver shaft, shaft extensions on the roller, gears connecting the driver shaft and one shaft extension in rotative relation, a slide bracket 10 carrying the respective ends of the shaft extensions and those of the driver shaft to cause said shaft and roller and connecting gears to move together, guide brackets for the slides, yieldable means for normally holding the roller and shaft to their adjusted position, and means for adjusting the slide brackets for the purposes specified.

6. In coal breakers, a pair of breaker elements, at least one of which comprises a rotatable breaker roller member mounted in co-operative relation to the other element, a driver shaft, shaft extensions on the rotatable roller, gears connecting the driver shaft and one shaft extension in rotatable relation, slide brackets carrying the respective ends 20 of the shaft extensions and those of the driver shaft to cause said shaft and rotatable roller and the connecting gears to move together, guide brackets for the slides, means for normally holding the roller and shaft to their adjusted position, and means for adjusting the slide brackets for the purpose specified.

JOSEPH T. NORMAN.
